UNITED STATES PATENT OFFICE.

WALTER C. REED, OF DALTON, MASSACHUSETTS, ASSIGNOR TO THE TELELECTRIC COMPANY, OF PITTSFIELD, MASSACHUSETTS, A CORPORATION OF MASSACHUSETTS.

CIRCUIT-CONTROLLER.

1,267,454.

Specification of Letters Patent. Patented May 28, 1918.

Application filed January 30, 1913. Serial No. 745,094.

To all whom it may concern:

Be it known that I, WALTER C. REED, a citizen of the United States residing at Dalton, in the county of Berkshire and State of Massachusetts, have invented new and useful Improvements in Circuit-Controllers, of which the following is a specification.

This invention relates to circuit-controlling devices of that type in which provision is made for opening and closing one or more electric circuits by electrically-operated means included in another circuit or circuits, and is particularly intended to provide a device of this character which will be serviceable for use in electrically-operated piano players for the purpose of opening and closing circuits which operate appliances for producing sustained expression effects in the compositions played. Accordingly, my improvements are herein shown and described as embodied in a circuit-controller designed for the specific purpose just referred to, and reside in certain features of construction and arrangement hereinafter explained in connection with the accompanying drawings, in which:

Figure 1 is an end elevation of my circuit controlling appliance as preferably constructed and arranged;

Fig. 2 is a front elevation of so much of the same as is behind the section line *x—x* in Fig. 1;

Fig. 3 is a top plan view of the same; and Fig. 4 is a central longitudinal section through one of the magnets illustrated in the other figures.

The particular form of circuit-controlling appliance herein described is adapted to secure independent control of four distinct circuits corresponding to four different expression-producing devices, such as, for example, the loud and soft pedals of a piano and resistance-varying arrangements for subduing the loudness of the notes struck by two independent groups of the piano keys, but it will be understood that my improvements may be utilized as well for controlling any desired number of circuits, from one upward.

In the drawings, 2 represents a base plate having mounted thereon a series of four electro-magnets 3, each of which is preferably of the solenoid type and has a plunger 4 arranged to move horizontally

within the magnet, as shown in Fig. 4. The magnets 3 may be constructed in any usual or suitable manner, but their plungers 4, instead of being constantly subjected to the action of a spring or gravity tending to move them in one direction, are in this case left free, so that when any plunger occupies either its outermost or its innermost position it will remain at rest without restraint until it is pulled inward by the corresponding magnet or until it is purposely moved outward, as the case may be.

In order to limit the range of movement of the plungers 4 and render their operation noiseless I provide the ends of each plunger 70 with reduced screw-threaded extensions 5 and 6 carrying felt disks 7 and 8 forming stops adapted to bring up against the corresponding ends of the magnet and separated by a distance equal to said range of movement, the disk 7 being backed up by an abutment 9 adjustably mounted on the threaded extension 5 and held in place by a lock nut 10, and the disk 8 being backed up by a tip 11 hereinafter described, which 75 is screwed onto the threaded extension 6. The main or unreduced portion of the plunger is located adjacent to one of the felt disks and thus determines the position assumed by the tip 11 when the corresponding 80 magnet is energized, and preferably, as in the example illustrated, the action of each magnet is to draw its tip toward it.

Each of the plungers 4 is adapted to open and close a corresponding circuit by 90 operating a contact device which is preferably constructed as shown in Figs. 1 and 2, in which 12 indicates a metallic strip shaped like an inverted U and fixed to an insulating block 13 carried by the base 95 plate 2, each strip 12 being located in front of the corresponding magnet 3, and 14 indicates a pair of spring wires secured at one end to the block 13 and having their free ends arranged to spring into contact 100 with the corresponding strip 12 on opposite sides of the latter when permitted to do so. Metallic clips 15 and 16 held in contact with the strip 12 and wires 14 respectively serve as a convenient means for connecting these 105 parts to the corresponding circuit wires 17 and 18, which form a part of a pedal-operating or other circuit to be controlled. It will be seen that the circuit through said wires 17 and 18 will be closed whenever 110

either of the corresponding wires 14 makes contact with its strip 12, but will be broken whenever both of the wires 14 are spread apart and so moved out of contact with said strip, and for spreading said wires 14 the tip 11 above referred to is utilized. This tip, which is made of hard rubber or other insulating material, is provided with a reduced portion 19 the diameter of which is less than the distance between the free end portions of the wires 14 when the latter are in contact with the corresponding strip 12, and with another portion 20 the diameter of which is greater than the distance above referred to. Between the portions 19 and 20 the tip has a tapering portion 21 adapted to act as a cam or wedge to force the wires 14 apart, and in the example illustrated, in which the closing of the circuits represented by the wires 17 and 18 is effected by the energizing of the corresponding magnets 3, the arrangement is such that the inward movement of each plunger 4 results in withdrawing the larger portion 20 of the tip 11 from between the wires 14, thereby permitting said wires to spring into contact with the strip 12 and close the circuit. The object of employing two wires 14 in each contact device is to make it certain that the circuit will be closed, even though one of the wires should accidentally become bent or the parts should be otherwise disarranged sufficiently to hold the wire on one side of the strip 12 out of contact therewith after the plunger has been drawn into its magnet.

After any one of the circuits through the wires 17 and 18 has been closed as above described by the energizing of the corresponding magnet 3, such circuit will evidently remain closed until the plunger 4 of that magnet is intentionally moved outward and caused to spread the corresponding wires 14 apart, whereupon the circuit will be opened and will remain open until the magnet 3 is again energized, since the lateral pressure of said wires upon the portion 20 of the tip 11 will have no tendency to move the plunger 4 in either direction. The plungers 4 of the various magnets 3, if several such magnets are employed, may be moved outward manually if desired, but preferably a supplementary electro-magnet is provided for the purpose, and in the construction represented provision is made for moving all of said plungers outward by means of a single supplementary magnet 22 located above the other four magnets at the middle of the series and clamped in place by a bar 23 secured at its ends to brackets 24 projecting upward from the base plate 2. Said magnet 22 may be of the same construction as the magnets 3, but the inward movement of its plunger 25 is in the opposite direction from that of the

plungers 4, and said plunger 25 is provided with a spring 26 for forcing it outward to the limit of such movement, which is determined by a stop 27 carried by one end of the plunger and adapted to abut against the adjacent end of the magnet 22. To the opposite end of the plunger 25 is attached a bar 28 carrying a series of fingers 29, one for each magnet 3, each finger being located in such position that whenever the magnet 22 is energized and its plunger is drawn inward (to the left as shown in Fig. 1) any of the plungers 4 which are in their innermost position at that time will be pushed outward and caused to spread the corresponding wires 14. Preferably the engaging ends of the fingers 29 are covered with felt, as shown at 30.

Metallic clips 31 secured to an insulating block 32 mounted on the base plate 2 serve as terminals for the coils of the several magnets 3 and 22 and are connected to the circuit wires through which said magnets are energized as desired. The wiring diagram is shown in Fig. 3, in which 33 indicates a wire connecting one of the clips 31 to one end of each of the coils of the magnets 3, the other ends of which coils are respectively connected by individual wires 34 to corresponding clips 31. The other two clips 31 are connected respectively to the ends of the coil of the supplementary magnet 22 by wires 35 and 36, and also to circuit wires 37 and 38 forming part of an individual energizing circuit for this magnet. Of the other circuit wires connected to the clips 31 the circuit wire 39 serves as a common return wire for all the magnets 3, while each of the other circuit wires 40 forms a part of the energizing circuit for one of said magnets only.

The operation of the apparatus, as described thus far, is as follows: Whenever the circuit through one of the wires 40 is closed the corresponding magnet 3 is energized and caused to close the circuit through the corresponding wires 17 and 18, which circuit will remain closed until the supplementary magnet 22 is energized by the closing of the circuit through the wires 37 and 38. When this occurs all of the circuits through the wires 17 and 18 which were previously closed are opened, and all the expression-producing appliances are therefore rendered inoperative until one or more of the circuits through the wires 17 and 18 are purposely closed by the energizing of the appropriate magnet or magnets 3. It is sometimes desirable, however, to open one or more of the previously-closed circuits through the wires 17 and 18 without affecting or preventing the simultaneous closing of some other one of these circuits, and this may be provided for by making the fingers 29 in the form of springs of such flexibility that whenever

any magnet 3 is energized its plunger 4 will be held in its innermost position against the pressure of the corresponding spring finger, even though the plunger 25 is drawn inward 5 by the energizing of the supplementary magnet 22. With this arrangement said magnet 22 and any of the magnets 3 may be energized simultaneously, and the result in such case will be that the plungers of those 10 magnets 3 which are energized will be drawn inward or so remain, while the plungers of any magnets 3 which are not energized at this time will be forced outward by the operation of the supplementary magnet 22, 15 which should obviously be so designed as to have sufficient power to draw its armature inward against the spring action of the fingers 29 as well as against the spring 26. It is to be observed, however, that it is not 20 essential to employ resilient fingers for the purpose just described, since practically the same result will be obtained if the momentary energizing of the magnet 22 is immediately followed by the energizing of that 25 magnet 3 which corresponds to the circuit desired to be kept closed. The same result will also be obtained if the circuit through the last-mentioned magnet is kept closed during the momentary actuation of the mag- 30 net 22, provided the latter is strong enough to overcome the pull of the magnet 3, since in such case the latter magnet will immediately become operative to draw in its plunger as soon as the magnet 22 is deener- 35 gized.

It will be obvious that the form and type of the magnets employed, as well as the other details of the construction illustrated, may be variously modified without departing 40 from my invention, and that my circuit controller may be used to advantage in a variety of situations where it is desired to control one or more electric circuits by a relay mechanism.

45 I claim:

1. A circuit controller comprising an electromagnet, a movable member subject to the attraction thereof, a contact device including two circuit terminals, a metallic strip 50 connected to one of the terminals and a pair of spring wires each connected to the other terminal and independently movable in opposite directions into contact with the metallic strip, and means carried by said movable member for spreading the spring wires in one position of the member and thereby moving both of them out of contact with the metallic strip, and for releasing said wires and permitting them to spring into contact 55 with the metallic strip in another position of said member.

2. A circuit controller comprising a solenoid having a plunger movable under the attraction thereof, a contact device including two circuit terminals, a metallic strip 65 connected to one of the terminals and a pair of spring wires each connected to the other terminal and independently movable in opposite directions into contact with said metallic strip, and an insulating tip carried 70 by said plunger and having two cylindrical portions connected by a tapering portion, said cylindrical portions being respectively of such diameters as to spread and release the spring wires. 75

3. A circuit controller comprising a plurality of independently-energized horizontal solenoids each having a free plunger movable inward thereby when energized and projecting at both ends beyond the ends of 80 the solenoid, contact devices each controlled by one end of one of said plungers, a supplementary horizontal solenoid having a spring-actuated plunger movable in one direction thereby when energized, and means 85 carried by the latter plunger for engaging the first-mentioned plungers and moving them outward independently of one another.

4. A circuit controller comprising a plurality of electro-magnets each having a free 90 member movable in one direction by the attraction of the corresponding magnet and adapted to remain without restraint in either of its extreme positions, a supplementary electro-magnet and yielding means operated 95 thereby for moving said members in the opposite direction independently of one another, and contact devices corresponding to independent circuits and each controlled by one of said members. 100

5. A circuit controller comprising a plurality of solenoids each having a free plunger movable in one direction thereby and adapted to remain without restraint in either of its extreme positions, a supplementary solenoid having a plunger movable in the opposite direction thereby, means for restoring the latter plunger to its normal position, a plurality of resilient fingers connected to the plunger of the supplementary solenoid and each located in position to engage one of the first-mentioned plungers at the limit of the inward movement of the latter, and contact devices each controlled by one of the latter plungers. 110 115

In testimony whereof, I have hereunto subscribed my name this 24th day of January, 1913.
